UNITED STATES PATENT OFFICE.

GEORGE Y. SMITH, OF MINNEAPOLIS, MINNESOTA.

METHOD OF AND APPARATUS FOR MANUFACTURING ARTIFICIAL FUEL.

SPECIFICATION forming part of Letters Patent No. 425,350, dated April 8, 1890.

Application filed December 17, 1889. Serial No. 334,102. (No model.)

To all whom it may concern:

Be it known that I, GEORGE Y. SMITH, a citizen of the United States, residing at Minneapolis, in the county of Hennepin and State 5 of Minnesota, have invented certain new and useful Improvements in the Method of and Apparatus for Manufacturing Artificial Fuel; and I do hereby declare the following to be a full, clear, and exact description of the invention, such as will enable others skilled in the art to which it appertains to make and use the same.

In many parts of the country, owing to the absence of timber and to the long distance 15 from beds of coal, the question of fuel is of paramount importance, and it has been a problem to devise ways and means for meeting the demands in this line. In these sections of country agriculture is the principal occupation followed by the inhabitants, and on every farm will be found large stacks 20 of straw, fodder, and other fibrous material, which are often allowed to go to waste. In these sections peat beds or bogs are also common, and the products of these beds would 25 make excellent fuel if properly prepared for utilization.

The primary object of my invention is to provide a method of and portable apparatus 30 for manufacturing artificial fuel from fibrous material, which apparatus can be hauled around the country in the manner now common with thrashing-machines and other analogous devices. It is obvious, however, that 35 the plant could either be stationary or portable; but for convenience of transportation I have shown it as of the latter form.

My apparatus comprises a series of devices for accomplishing the purpose set forth, and 40 is shown as carried by a truck, wagon, or other vehicle.

The fibrous material to be converted into fuel is fed by means of rolls or other equivalent appliances to a cutter for separating it 45 into small pieces or fragments, which drop into a vat or receptacle in communication with a tank containing oil or other inflammable liquid intermixed with other ingredients. While in this vat the material is thoroughly 50 saturated with the inflammable ingredients,

is commingled therewith and at the same time fed longitudinally of the vat by a revolving agitator-screw mounted therein, and passes between a pair of rollers, which express all superfluous oil and deliver it in the shape of 55 a flat sheet to a device consisting of a cylinder and concave armed with teeth for breaking up and thoroughly disintegrating the material. The mixing-vat is surrounded by a chamber, in which steam is introduced for 60 the purpose of keeping the contents of the vat in the proper condition, and the rollers at the end of the vat are hollow and are heated by steam to prevent them from chilling the material. An elevator conveys the material 65 disintegrated by the cylinder and concave through a case which forms the outlet of a fan-box and delivers it into a hopper, from which it is fed by rollers or other equivalent devices to a contrivance for pressing it into 70 the form of bricks or blocks, the completed bricks being delivered from this contrivance upon an endless belt, which conveys them to the desired place. As the material is carried up by the elevator, it is slightly cooled by 75 the blast from the fan-box and is thereby placed in proper condition to be molded into the form desired.

The invention consists in the method of and apparatus for manufacturing artificial 80 fuel, as will be hereinafter described, and particularly pointed out in the claims.

Referring to the accompanying drawings, in which like symbols denote like parts throughout the several views, Figure 1 is a plan view, 85 partly in section, of an apparatus constructed in accordance with my invention. Fig. 2 is a longitudinal vertical section thereof. Fig. 3 is a vertical section of a tank in which the oil and other inflammable ingredients are 90 mixed and prepared. Figs. 4 and 5 are detail views of the molds in which the material is compressed into brick form.

A is a wagon, truck, or other vehicle, upon 95 which the parts of my apparatus are shown as mounted, although they can be located as fixtures in a building, if deemed desirable.

B is a chute or box along which the material to be converted into fuel is fed to a pair of rolls C.

- D is a cutter, shown as a cylinder with a spirally-arranged knife, although it may be of any other well-known form, which severs the material into bits or pieces.
- 5 E is a vat of conical form into which the severed material falls, and e is a steam-chamber surrounding said vat.
- F is a tank in which the inflammable ingredients are mixed and prepared.
- 10 f is a shaft driven by suitable gearing and carrying wings or blades f', and f² are stationary wings projecting from the inside of the tank.
- f³ is a steam-chamber surrounding the tank, and f⁴ is the steam-delivery pipe.
- 15 f⁵ is a pipe communicating with tank F and serving to deliver its contents into vat E, and f⁶ is a cock or valve in said pipe.
- G is a feed-screw located in vat E and provided with wings or agitators g'. The shaft of said screw is provided with a gear-wheel g² in mesh with another gear g³ on a transverse shaft g⁴. H H' are hollow rolls located at and closing the inner end of conical vat E,
- 25 said rolls serving to compress the material exuding from the vat into sheet form and to express all surplus oil therefrom, which oil runs back into the vat.
- I is a toothed cylinder working in conjunction with an adjustable concave J, said cylinder and concave serving to break up and disintegrate the sheet as it issues from between the rolls.
- 30 j j are bolts and slots for adjusting the concave.
- K is an elevator, shown as of the belt kind, provided with cups k k, which receive the disintegrated material falling from the concave J and deliver it to a pair of rolls M M,
- 35 mounted in a hopper N, located over the compressing mechanism.
- O is a fan mounted in a fan-case O', which not only surrounds the fan, but is extended up over the elevator-belt.
- 40 P and P' are wheels or drums provided with registering recesses or pockets p p', which receive the material from hopper N and press or mold it into brick form.
- 45 p² are compressing-pistons in the pockets of wheel P'.
- 50 p³ p³ are rods loosely mounted in wheel P' and attached to each piston p².
- 55 p⁴ is a stationary cam, over the surface of which the rods travel and which serves at the proper time to drive the piston forward and force the contents of filled pocket p' into the filled pocket p.
- 60 p⁵ is a block with a threaded opening for receiving a screw p⁶, by which it can be adjusted back and forth to vary the position of the piston in the pocket. (See Fig. 5.)
- 65 p⁷ are compressing and discharging pistons in the pockets of wheel P, and p⁸ and p⁹ are stationary cams for actuating said pistons.
- 70 Q is an endless delivery-belt located below the forming-wheels.
- R is a steam-pipe coupled to a two-way connection in communication with pipes r r' for delivering steam to shell e and rolls H H'.
- The various devices of the apparatus are 75 geared together and driven in the following manner: It is to be understood that a portable steam-engine is to accompany the apparatus and that the mixing-vat F is to be carried by a suitable truck. It is also to be understood 75 that the exhaust-steam from such engine will be utilized to heat the tank, vat, and rolls. Power is applied by a belt from the engine to a pulley 1 on one end of the shaft i of the cylinder I. On the other end of said shaft is a 80 spur-gear 2 and sprocket-wheels 3 and 4. A sprocket-chain 5 connects wheel 3 with a similar gear on the cutter-shaft d. Spur-gear 2 engages with a gear 6 on shaft 1', carrying pulley L', said shaft being also provided with another gear 7, which drives a train of gears 8 9 10 for actuating the forming-wheels P and P'. On the end opposite spur-gear 6 shaft 1' is provided with a sprocket-gear 11, from which a chain passes to a gear 12 on the shaft h of 85 roll H and to a gear 13 on the end of shaft g⁴. 14 is a sprocket-wheel on the other end of shaft h, from which a chain 15 passes to a sprocket-gear 16 on the end of feed-roll C. The fan-shaft o is driven from wheel 4 on shaft 90 i by suitable sprocket-gearing, (see dotted lines in Fig. 2,) and the rolls M M in hopper N are driven by sprocket-gearing from the shaft on which wheels 8 and 9 are mounted. Shaft 17 of the mixing-tank is provided with 95 a pulley 18, driven by a separate belt from the engine, and has a bevel-gear 19 in engagement with a like gear 20 on shaft f.
- 100 While I have shown and described a particular arrangement of gearing for connecting the various parts of the apparatus, yet it is distinctly to be understood that the parts could be geared up in any appropriate manner within the province of the skilled mechanic, and that they could be arranged in other positions than those shown without departing from my invention.
- 105 In operation petroleum residuum or other oil rich in hydrocarbons, pitch, rosin, and it may be other inflammable materials, are 110 placed in tank F, and while being reduced to a fluid condition by steam introduced in chamber f³ are thoroughly stirred and intermixed with each other by the rotary blades and stationary wings. Straw, peat, or other analogous fibrous material placed on platform B is advanced to roll C and fed forward to cutter D, by which it is cut into short bits or pieces, which drop into vat E. Tank F is located at the desired height above vat E, so that when 115 cock f⁶ is turned the oily mixture can flow from said tank and be incorporated with the short pieces of material in the vat. Screw G thoroughly stirs the material in the vat until it becomes saturated with the oily mixture, 120 and at the same time continually feeds it along until it is seized by the hollow steam-
- 125 130

heated rolls H H', which compress the material into the form of a flat sheet and also express all surplus oil therefrom and permit it to return to the vat. As the sheet of material 5 exudes from between the rolls, it is caught between the toothed cylinder and concave and is thoroughly broken up and disintegrated, the fragments falling upon and being received by the cups of the elevator-belt. As the material 10 may still be in a too fluid condition to be pressed into brick form, it is subjected to a blast of cold air from the fan as it is being carried up by the elevator-buckets, which sufficiently cools and sets it to enable the succeeding 15 steps successfully to be carried out. From the buckets the material drops into hopper N and between the rolls M M', from which it passes to the forming-wheels P P', where it is pressed into the form of bricks or blocks, 20 which are delivered upon the traveling apron or belt and are conveyed thereby to the desired place.

While I have shown an apparatus for carrying out the various steps of my improved 25 method, yet it is to be understood that it can be successfully practiced by other means or by hand.

No claim is made herein to the forming-wheels provided with registering peripheral 30 molds containing radially-movable pistons adapted to compress the contents of the two molds into one when in registration, as these are set forth and claimed in an application filed by me July 29, 1889, Serial No. 318,992.

35 Having thus described my invention, what I claim as new is—

1. The method of manufacturing artificial fuel, consisting in first severing fibrous material into short bits or pieces; second, thoroughly mixing and saturating the same with oil or other inflammable mixture; third, compressing this material to free it from surplus oil; fourth, disintegrating the compressed material, and, fifth, molding or pressing it 45 into the form of bricks or blocks, substantially as and for the purpose specified.

2. The method of manufacturing artificial fuel, consisting in first mixing and saturating fibrous material with an inflammable mixture; 50 second, compressing the material into the form of a flat sheet and expressing the surplus mixture therefrom; third, disintegrating the sheet; fourth, cooling the disintegrated material; and, fifth, compressing it into the form 55 of bricks or blocks.

3. The method of manufacturing artificial fuel, comprising the following steps: first, cutting fibrous material into short bits or pieces; second, thoroughly mixing and saturating 60 these pieces with oil or other inflammable material; third, compressing the material; fourth, breaking up and disintegrating the material; fifth, cooling the same, and, sixth, molding it into the desired form, substantially as set 65 forth.

4. An apparatus for the manufacture of artificial fuel, comprising means for feeding and severing fibrous material into short bits or pieces, a vat or receptacle for receiving said pieces, and means therein for mixing and 70 incorporating them with an oily mixture, and rollers at the end of said vat for compressing the material into the form of a flat sheet and expressing the surplus oil therefrom, substantially as set forth. 75

5. An apparatus for the manufacture of artificial fuel, comprising means for feeding fibrous material and for severing it into short bits or pieces, a vat for receiving said pieces in communication with a tank containing a 80 supply of oil or other inflammable material, a screw in said vat for thoroughly mixing and incorporating the ingredients, rollers at the end of the vat for compressing the material into the form of a flat sheet and expressing 85 the surplus oil therefrom, and a toothed cylinder and concave for breaking up and disintegrating said sheet, substantially as and for the purpose set forth.

6. An apparatus for the manufacture of 90 artificial fuel, comprising means for severing fibrous material into short bits or pieces, a steam-heated vat containing a supply of oil for receiving said pieces, a screw in said vat for mixing and feeding along the contents of 95 said vat, and a pair of steam-heated rolls at the end of said vat, substantially as and for the purpose set forth.

7. An apparatus for the manufacture of 100 artificial fuel, comprising means for mixing fibrous material with oil or other inflammable substance, rollers for compressing the material into sheet form, a toothed cylinder and concave, an elevator, and means for delivering a blast of air upon the material as it is 105 being carried up by the elevator, substantially as set forth.

8. In an apparatus for the manufacture of 110 artificial fuel, the combination of a steam-heated vat, a feed-screw in said vat, rollers at the end of the vat, a toothed cylinder and concave, an elevator, a fan and fan-case, and devices for molding the material delivered by the elevator, substantially as set forth.

9. A portable apparatus for manufacturing 115 artificial fuel, comprising the following instrumentalities in combination: devices for feeding and severing fibrous material into short bits or pieces, a vat for receiving said pieces, a feed-screw in said vat, rollers at the 120 end of the vat, means for breaking up and disintegrating the material delivered from the rollers, an elevator, a fan and fan-case, and a pair of wheels having devices for molding the material, substantially as and for the 125 purpose set forth.

10. The combination, with a wheel having a peripheral mold, of a radially-movable piston in said mold, a block having a threaded opening between the piston and the bottom 130

wall of the mold, and a screw having its head seated in the piston and its threaded portion entering said block, substantially as and for the purpose set forth.

5 11. An apparatus for manufacturing artificial fuel, comprising a vat, a feed device in said vat, rollers at the end of the vat, a toothed cylinder and concave, an elevator, and device for molding the material delivered

by the elevator, substantially as and for the purpose specified.

In testimony whereof I affix my signature in presence of two witnesses.

GEO. Y. SMITH.
